UNITED STATES PATENT OFFICE

93,936

DESIGN FOR A DRESS

Eleanor Mair, New York, N. Y.

Application September 8, 1934, Serial No. 53,230

Term of patent 3½ years

To all whom it may concern:

Be it known that I, ELEANOR MAIR, a citizen of the United States of America, residing in Manhattan, in the county of New York and State of New York, have invented the new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The characteristic feature of the design resides in the collar member, composed of two portions, the one superposed upon the other, the under portion being of a material contrasting in texture and design to the upper portion, the corner portions also embodying ruffled inserts. Another feature of the design resides in the frilled inserts made of two contrasting materials included at the lower part of the sleeve, as shown.

I claim:

The ornamental design for a dress, substantially as shown and described.

ELEANOR MAIR.
